UNITED STATES PATENT OFFICE.

DAVID G. MORGAN, OF RUTLAND, VERMONT.

RAILROAD TIME-SIGNAL.

SPECIFICATION forming part of Letters Patent No. 341,343, dated May 4, 1886.

Application filed May 14, 1885. Serial No. 165,484. (No model.)

To all whom it may concern:

Be it known that I, DAVID G. MORGAN, a citizen of the United States of America, residing at Rutland, in the county of Rutland and 5 State of Vermont, have invented certain new and useful Improvements in Railroad Time-Signals; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 My invention relates to railroad time-signals; and it consists in the improvements hereinafter described and set forth.

In the accompanying drawings, which illustrate my invention, Figure 1 is a side view of 20 my improvement. Fig. 2 is also a side view taken from the opposite side of the apparatus, and Fig. 3 is a plan view, and Fig. 4 is a modification, of my improvement.

A represents a suitably-constructed frame, 25 which consists of upright bars *a a*. Between these bars is located a suitable clock mechanism, B, which is located between plates B'. The train of gear-wheels B is provided with suitable balance-wheel and a spring or detent, *b*, 30 by means of which the movement of the train of gear-wheels is regulated.

C represents a main gear wheel, which is attached upon a shaft which passes through the plates B', so that said wheel C will project 35 beyond the casing. This wheel C is provided on its inner side with the ratchet-wheel *c* and a pawl, *c'*, and the wheel C, hereinbefore referred to, is so connected to its shaft that it may turn freely thereon in one direction, but 40 will cause the shaft to rotate when turned in an opposite direction. The casing or covering-plates B' are rigidly attached between the parts *a a* of the frame by means of straps or other equivalents, *b'*.

45 Brackets or plates D D' are attached to the same side of the frame on which the wheel C is located, and these brackets serve as guides and supports for a signal-rod, E, which passes through perforations in the horizontal projecting portions of said brackets.

To the lower bracket, D, is attached a short

section of pipe or tube, *e*, which is provided under said bracket with a longitudinal spiral slot, *f*, which extends half-way round said tube, and the signal-rod is provided with a pin or 55 bolt, *f'*, which passes through said slot, so as to cause said signal-rod to turn one-half way round when said signal-rod is elevated.

G represents a suitable sliding tube or bar, which is provided with a socket through 60 which passes the signal-rod E, and adjacent to said socket the sliding piece G has attached a rack-bar, *g*, which rack-bar engages with the gear-wheel C, which is connected to the train or clock-work, so as to wind the same 65 when said bar is raised.

The location of the rack-bar *g* and the socket may be changed by moving the block H, which embraces the signal-rod, and is provided with the clamp-screw *h*, which passes 70 through said block and bears upon the signal-rod, and said block is independent or not directly connected with the sliding piece G. The object of this block is to regulate the movement of rack *a*.

75 The sliding piece G is pivotally connected at its lower end to straps *I I*, which are secured to the end of a lever, J, said lever being supported adjacent to the rail of the track by a bracket, K, as shown. The lever near its end 80 adjacent to the railroad-track rests upon a pivoted pin, *k*, a groove being provided in the under side of said lever, which fits over the pin *k*, and the upper part of the side pieces of the bracket K has a transverse pin, *k'*, which passes 85 through the same and over the upper edge of the lever, thus preventing the upward displacement of said lever. By this construction the lever J is attached to its support, so that no strain is placed upon the parts by the contraction or expansion of the lever. The end of the lever adjacent to the railroad-rail is enlarged, as shown in Figs. 1 and 2, and its upper edge presents the segment of a circle, so that the car-wheels will ride easily over the 90 same, and the tread of the rail is cut away or recessed for the reception of this enlarged end.

95 The bracket D, which is secured to the frame, is provided with upwardly-projecting supports L for the lever or pivoted bar Q, one end of 100 which is bifurcated, so as to embrace the signal-rod and bear upon the lower edge of the

sliding piece G. The opposite end of this pivoted bar Q is pivotally connected to a vertical rod, N, the upper end of which is reduced in diameter, so as to provide a collar, n, near its upper end, and said reduced portion passes through an eye or guide, n'.

The upper bracket, D', has attached to its under side supports m m to which is secured, an angle-bar, M, the end o of said angle-bar being provided with an opening through which passes the reduced portion of the rod N, so that it may rest upon the shoulder n. The opposite end of the bar N is provided with the depending catch O, which is formed integral therewith, and said catch is adapted to engage with an adjustable block, P, attached to the signal-rod E, the lower portion of said block being bell-shaped, as shown. The catch of the bar M is curved on its face, as shown. The normal condition of the parts of my improved railroad-signal is shown in the accompanying drawings, and when a train passes over the end of the lever J the long end of the same will be elevated, this movement causing the signal-rod E to be raised and turned one-half way round. The rack-bar g is also raised, and contacting with the large wheel C will cause the same to turn when the slide-piece G is raised. The catch O on the bar M will then engage with the block P and hold the signal-rod elevated. As soon as the train has passed over the end of the lever J the slide-block, with the rack-bar, will commence to descend, its movement being retarded by gearing or clock-work which may be adjusted so that it will take a predetermined or certain period of time between the commencement and end of the descent of said sliding bar. When said sliding bar descends sufficiently to come in contact with the bifurcated end of the lever Q, it will depress said bifurcated end and cause the bar N to rise, which contacts with a lever, M, so as to release its catch from the block P, attached to the signal-rod. The signal-rod will then fall and resume its normal position. By this arrangement trains will be prevented from running into each other from the rear, and they may be kept by means of the improved signal hereinbefore described certain distances apart. In the accompanying drawings, Fig. 4 is a modification of my improvement, in which case the construction is varied slightly so as to provide for turning the signal-rod without elevating the same, the rotary movement being caused by raising the rack-bar g so as to elevate the grooved sleeve G. The signal-rod is made fast at its lower end to the frame I', and the straps I are connected to the rack-bar. By this construction no jar can come upon the signal-rod when it is turned. The sliding pieces G e, through which the signal-rod passes,

are provided with wings which are slotted and attached to the frame, so that they can slide upon the same.

It will be obvious that day or night signals of any suitable construction may be employed, or that a semaphore or lantern may be connected or attached to the signal-rod, and that any suitable arrangement of gears or a revolving fan or other devices may be used to retard the action of the descending rack-bar, so as to prolong the time between the change of the signal.

I claim—

1. The combination, in a railroad-signal, of a vertically-moving rod carrying a visible signal, a sliding rack-bar adapted to move upon said signal-rod, blocks secured to said signal-rod, a lever supported adjacent to the railroad-track and connected to said rack-bar, a train of gearing, B, a wheel, C, engaging with said rack-bar and connected to said train of gearing B, pivoted levers Q and M, a rod, N, connecting said levers, and a catch, O, engaging one of said blocks, as shown, whereby the signal-rod is held in position to display the signal till the rack-bar descends sufficiently to release a supporting-catch, substantially as shown, and for the purpose set forth.

2. In a railroad-signal, the combination, with a lever, J, a rack-bar, and straps I, connecting said lever to said rack-bar, of the signal-rod having attached thereto blocks H P, and a pin, f', a socket, e, with grooves f, levers Q M, having a catch, O, and connecting-rod N, and gear-wheels, the parts being organized substantially as shown, and for the purpose set forth.

3. In a railroad-signal, a rod, a signal mounted thereon, a lever adapted to be operated by a passing train to vertically move said rod, a grooved socket through which said rod passes, a pin in the signal-rod and extending into the groove, blocks H P, attached to the signal-rod, a sliding rack-bar having a socket through which the signal-rod passes, links I I, connecting the rack-bar with the operating-lever, the pivoted lever Q, having a bifurcated end which embraces the signal-rod, and bar N, having a reduced end, a pivoted lever, M, the end of which embraces said reduced end, a catch, O, formed integrally with said lever M, a wheel, C, meshing with rack-bar, and retarding mechanism connected with said wheel C, substantially as set forth.

In testimony whereof I affix my signature in presence of two witnesses.

DAVID G. MORGAN.
